(57) **CLAIM**

The ornamental design for a desktop touch screen, as shown and described.

DESCRIPTION

FIG. 1 is a front view of the desktop touch screen of the present invention;

FIG. 2 is a right side view of the desktop touch screen of FIG. 1;

FIG. 3 is a left side view of the desktop touch screen of FIG. 1;

FIG. 4 is a top view of the desktop touch screen of FIG. 1; FIG. 5 is a rear view of the desktop touch screen of FIG. 1; and,

FIG. 6 is a rear perspective view of the desktop touch screen of FIG. 1.

The broken line showing of structural features is included for the purpose of illustrating non-claimed subject matter and forms no part of the claimed design.
